UNIVERSAL SANDING BLOCK

Jose A. Lugo, Ridgewood, N.Y., assignor to Jose A. Lugo, Ridgewood, N.Y.

Filed Oct. 2, 1974, Ser. No. 511,169

Term of patent 7 years

Int. Cl. D8—05

U.S. Cl. D8—90

Fig. 1

Fig. 2

FIG. 1 is a side elevation of a sanding block showing my new design.

FIG. 2 is a sectional view of FIG. 1, omitting the handles.

FIG. 3 is a perspective view of FIG. 1.

I claim:

The ornamental design for a universal sanding block, as shown and described.
